GÜSTAV WILHELM MAXIMILIAN CONZ, OF ULM, WÜRTEMBERG, GERMANY.

ELECTRICAL SIGNAL APPARATUS.

SPECIFICATION forming part of Letters Patent No. 416,572, dated December 3, 1889.

Application filed October 5, 1887. Serial No. 251,493. (No model.) Patented in Germany January 18, 1887, No. 44,338; in Italy May 26, 1887, No. 21,784; in England June 1, 1887, No. 7,953; in Spain June 3, 1887, No. 11,391, and in Austria-Hungary May 4, 1888, No. 4,717 and No. 14,517.

To all whom it may concern:

Be it known that I, GÜSTAV WILHELM MAXIMILIAN CONZ, of Ulm, Würtemberg, Germany, have invented certain new and useful Improvements in Electrical Signal Apparatus, (for which I have obtained Letters Patent in Great Britain, No. 7,953, dated June 1, 1887; Germany, No. 44,338, dated January 18, 1887; Spain, No. 11,391, dated June 3, 1887; Italy, No. 21,784, dated May 26, 1887, and Austria-Hungary, No. 4,717 and No. 14,517, dated May 4, 1888,) of which the following is a specification.

This invention relates to a new and improved apparatus for transmitting one or more signals electrically by means of a single key to a single or several stations, this apparatus being specially adapted for giving signals at railway-stations, switch-houses and crossings, telegraph-stations, for signaling on ships, and for transmitting military signals.

The invention consists in the combination, with a series of wires arranged concentrically and each connected with a line-wire, of a rotative contact-closing arm the center of rotation of which is at the center of the concentric wires, said arm serving to bring the line-wire connected with it in circuit with one or more of the said concentric wires, according to the signal to be sent.

The invention also consists in the construction and combination of parts and details, as will be fully described and set forth herein-after, and finally pointed out in the claims.

In the accompanying drawings, Figure 1 is a cross-sectional view of that construction of the apparatus which it must have when used with a permanent source of electricity, such as a dynamo-electric machine. Fig. 2 is a plan view of the construction shown in Fig. 1, parts being omitted. Fig. 3 is a diagrammatic view of the construction shown in Fig. 2.

Similar letters of reference indicate corresponding parts.

On the insulated base-plate J' a number of (in this case six) upright segmental metal blocks M' M² M³ M⁴ M⁵ M⁶ are secured around a common center, the circle being completed by segmental blocks or pieces J of insulating

material placed between the blocks M' M², &c. The top edges of the blocks M' M², &c., and the insulating-pieces J are on the same level, said top edges being beveled to form a wedge-shaped annular track on which a roller r can run, said roller being pivoted in the forked end of an arm c, projecting from a cylindrical piece C, mounted to turn on the rounded part of a vertical spindle x in the center of the circle formed by the blocks M' M², &c., and the insulating-pieces J. The lower part of said spindle x is squared, so as to prevent the spindle from turning, and the lower end of the spindle is guided in a suitable socket in the base-plate J'. Above 65 said socket a sleeve k is held by means of a binding-screw a on the spindle x, said sleeve being insulated, as shown in Fig. 3, and connected by a flexible wire b¹ with the dynamo D². Against one side of the sleeve k 70 three contact-pieces g' g² g³ rest, which are secured to the upper ends of springs f' f² f³, connected, respectively, with the resistance-coils R', R², and R³, located within the circle formed by the segmental blocks M' M², &c., 75 and the insulating-pieces J, said resistance-coils being connected by suitable wires with the dynamo. The pieces g' g² g³ are arranged, as shown in Fig. 1, one above the other, so that by raising the spindle x the sleeve k 80 successively slides off the said pieces g' g² g³—that is to say, the contact between the sleeve and said pieces is successively broken. The contact-stud b' is formed at the opposite side of the sleeve k on the upper end of an upright spring b. A brush b³ is secured to the upper end of the spring b and bears against the spindle x for the purpose of conducting the current that passes from the sleeve k into the contact-piece b' to the spindle x, arm c, 85 and roller r. Said contact-piece b' is located such a distance above the top of the sleeve k that when the sleeve is moved upward sufficiently to break the contact between it and the lowest contact-piece g' the upper part of 90 the sleeve will be in contact with the contact-piece b'. A tongue A projects from the spindle x, and can pass into recesses C', of varying depths, extending upward from the bottom edge of the cylindrical piece C. A 100

sleeve h , surrounding the spindle x , has its lower end connected with the cylindrical piece C , and is passed through the cover W' of the casing W , surrounding the apparatus, 5 and to the top of said sleeve h a pointer z is secured, which extends over the top of the casing in the same direction as the arm c . A knob T is mounted on the upper end of the spindle x in such a manner that it can 10 be used to raise the spindle, but can turn on said spindle. To the bottom of the knob T the plate T' is secured, which is provided with apertures T' , into which a pin p can pass, that projects upward from the inner 15 end of the pointer z . An annular scale W^2 is fixed on the top of the cover W' , and on it the marks or characters are to be produced which represent the different signals.

Three concentric circular wires Nos. 1, 2, 20 and 3 surround the circle formed by the metal blocks and insulating-pieces, and are brought in electrical connection with the various blocks by passing through brackets or projections M on the outer faces of the 25 said blocks. For instance, the block M' is connected with all three wires 1, 2, and 3, as shown in the left-hand side of Fig. 1, whereas the block M^4 (shown on the right-hand side of Fig. 1) is only connected with one of the 30 wires, in this case No. 2. The wires $L' L^2 L^3$ are connected with the wires 1, 2, and 3, as shown in Fig. 1 by the dotted lines.

With this machine a permanent source of electricity—such as a dynamo-electric machine—is used.

The operation is as follows: In the construction shown in Figs. 1 and 2 the knob T is lowered, so that the pin p can pass through one of the apertures T' , and is turned until 40 the pointer z points to one of the signal-marks on the scale W^2 . Thereby the sleeve h and circular piece C are also carried around and the roller r is brought upon the top edge of that metal block M' or M^2 which corresponds 45 to the desired signal. For example, in Fig. 1 the block M' is connected with all three wires 1, 2, and 3. The current now passes from the dynamo-machine D^2 to the sleeve k , the contact-pieces $g' g^2 g^3$, the springs $f' f^2 f^3$, the 50 resistance-coils $R' R^2 R^3$, and back to the dynamo. None of the current passes through the line-wires. To give the signal, the spindle x is raised by pulling the knob T upward as far as the corresponding recess in the cylinder C allows. The result is that the sleeve k is raised and brought in contact with the contact-piece b' and out of contact with all 55 three contact-pieces $g' g^2 g^3$, so that all the current from the dynamo-machine now passes 60 to the sleeve k , the contact-piece b' , spindle x , the arm c , and roller r to the metal block M' , and all the three wires 1, 2, and 3, wires $L' L^2 L^3$, and the line-wires, and back to the dynamo. When the arm c is in such a position 65 that its roller r rests upon the block M' , the cylinder C is in such a position that its deepest notch C' is directly above the tongue

A of the spindle x , permitting of lifting the said spindle x to its greatest limit. After the signal has been given the knob T and the 70 spindle x are depressed. If a signal is to be given through the block M^4 , which is connected with the wire 2 only, the knob T is turned until the pointer z points to the corresponding mark on the scale W^2 , when the 75 roller r rests on the block M^4 . If the spindle x is now raised, the tongue A passes into a notch C' in the cylinder C of such depth that the sleeve k can only be raised sufficiently to disengage it from the contact-piece g' , said 80 sleeve still remaining in contact with the contact-pieces $g^2 g^3$, at the same time being in contact with the contact-piece b' . The result is that one-third of the current passes through the contact-piece b' , the spindle x , arm c , 85 roller r , metal block M^4 , wire No. 2, wire L^2 , and to the corresponding line-wire, and back to the dynamo, the remaining two-thirds of the current passing through the resistance-coils $R^2 R^3$ and back to the dynamo. With 90 this apparatus six signals can be given, one on each signal-wire Nos. 1, 2, and 3, one on the two wires Nos. 1 and 2 together, another on the wires Nos. 2 and 3 together, and one on all three wires, as the blocks $M' M^2$, &c., 95 are connected accordingly with the wires 1, 2, and 3.

For the first three signals only one of the resistance-coils $R' R^2 R^3$ will be cut out. For the fourth and fifth signals given on two 100 wires two of the resistance-coils are cut out, and for the signal given on all three wires all three of the resistance-coils are cut out.

It is evident that the contact-pieces $g' g^2 g^3$ need not necessarily be constructed in the 105 manner described, but may be arranged with yielding spring contact-pieces of any well-known construction.

Having thus described my invention, I claim as new and desire to secure by Letters Patent— 110

1. The combination of a number of concentric wires, a central post, conductive blocks, some of which are connected with one and some with two or more of said wires, an arm mounted to turn on the central post and 115 to run on said blocks, a conducting-wire connected with the central post, and a wire connected with each of said concentric wires.

2. The combination of a number of concentric wires, conductive blocks, some of which are connected with one and some with two or more of said wires, resistances connected with the source of electricity, a central post connected with the source of electricity, a circuit-closing arm on the center 120 post, and switching devices located between the resistances and the circuit-closing arm. 125

3. The combination of a number of segmental conductive blocks disposed in a circle and insulated from each other, a series of 130 electric circuits, each of said circuits being connected separately to some of said conductive blocks, jointly with each of the other circuits to other of said blocks, and jointly

with all the other circuits to another of said blocks, a center post, and a circuit-changing arm on said post provided with a roller which swings in contact with said segments.

5 4. The combination of a circular track composed of segmental conductive blocks and segmental insulating-blocks disposed in alternation, a series of concentric wires encircling said track, each of said wires being connected 10 separately to some of said conductive blocks, jointly with each of the other wires to other of said blocks, and jointly with all the other wires to another of said blocks, electric circuits connected, respectively, with said concentric wires, a center post, and a circuit-changing arm on said post, provided with a roller which travels on said track.

5 5. The combination of a sliding spindle provided with a laterally-projecting tongue, 20 a sleeve on said spindle, a cylindrical piece at the lower end of said sleeve provided with slots of different depths engaged by said tongue when the spindle is raised, an insulated sleeve on said spindle, contact-pieces 25 disposed one in advance of another normally in contact with said sleeve, and a contact-stud electrically connected with said spindle and disposed in the path of said insulated sleeve.

30 6. The combination of a sliding spindle provided with a laterally-projecting tongue, a sleeve on said spindle, a cylindrical piece at the lower end of said sleeve provided with slots of different depths engaged by said tongue when the spindle is raised, an insulated sleeve on said spindle, contact-pieces 35 disposed one in advance of another normally in contact with said sleeve, a contact-stud electrically connected with said spindle and 40 disposed in the path of said insulated sleeve, a pointer attached to the upper end of the sleeve first above mentioned, and a knob on said spindle for raising it.

45 7. The combination of a sliding spindle provided with a sleeve fixed thereon and insulated therefrom, a circuit-changing arm on said spindle, contact-pieces disposed one in advance of another normally in contact with said sleeve, resistances connected, respectively, with said contact-pieces, and a contact-stud electrically connected with said arm and 50 disposed in the path of said sleeve, whereby as the spindle is moved and said sleeve brought in contact with said stud one or more 55 of said contact-pieces are released from contact with the sleeve and one or more of the resistances cut out.

60 8. In an electric signaling apparatus, the combination, with a series of concentric wires, of metal blocks with which one or more of the wires are connected, a post or spindle at the center of the circular wires, an arm on the same, resistance-coils, a series of spring-contacts connected with the resistance-coils, 65 a sleeve on the post, against which sleeve the said contact-pieces rest, and a contact-spring adjacent to said collar, which contact-spring is

connected electrically with the arm on the center post, substantially as shown and described.

70

9. In an electric signaling apparatus, the combination, with a series of concentric wires, of metal blocks connected with one or more of the wires, a sliding spindle or post at the center of the circles described by the wires, a 75 rotative contact-closing arm mounted to turn on said spindle and running on the said metal blocks, a cylindrical piece at the inner end of said rotative contact-closing arm, which cylindrical piece has recesses in its bottom edge, a tongue projecting from the spindle and adapted to pass into said recesses, a sleeve on the sliding spindle or post, contact-pieces resting against the sleeve and connected electrically with resistances, and a contact-piece 80 at the side of the sleeve, which contact-piece is connected electrically with the rotative arm on the spindle, substantially as set forth.

10. In an electrical signaling apparatus, the combination, with the concentric wires 1, 2, and 3, of the metal blocks $M' M^2$, &c., connected with one or more of the wires, the insulating-pieces J between the metal blocks, the sliding spindle x , the resistances $R' R^2 R^3$, the contact-pieces $g' g^2 g^3$, connected with 95 the resistances, the sleeve k on the spindle, the contact-piece b' on the spring b , the tongue A on the spindle, the arm c , mounted to turn on the spindle and provided with the roller r , running on the upper edge of the 100 metal blocks, and the cylindrical piece C on the inner end of the arm c , which piece is provided with recesses C' in its lower edge, substantially as shown and described.

11. In an electric signaling apparatus, the combination, with the concentric wires 1, 2, and 3, of the metal blocks $M' M^2$, &c., connected with one or more of the wires, the insulating-pieces J between the metal blocks, the sliding spindle x , the resistances $R' R^2 R^3$, the contact-pieces $g' g^2 g^3$, connected with 110 the resistances, the sleeve k on the spindle, the contact-piece b' on the spring b , the tongue A on the spindle, the arm c , mounted to turn on the spindle and provided with the roller r , running on the upper edge of the 115 metal blocks, and the cylindrical piece C on the inner end of the arm c , which piece is provided with recesses C' in its lower edge, the sleeve h , the pointer z , and scale W^3 , substantially as shown and described.

12. In an electric signaling apparatus, the combination, with the concentric wires 1, 2, and 3, of the metal blocks $M' M^2$, &c., connected with one or more of the wires, the insulating-pieces J between the metal blocks, the sliding spindle x , the resistances $R' R^2 R^3$, the contact-pieces $g' g^2 g^3$, connected with 125 the resistances, the sleeve k on the spindle, the contact-piece b' on the spring b , the tongue A on the spindle, the arm c , mounted to turn on the spindle and provided with the roller r , running on the upper edge of the 130 metal blocks, and the cylindrical piece C on

the inner end of the arm c , which piece is provided with recesses C' in its lower edge, the sleeve h , the pointer z , and scale W^3 , the pin p , and the knob T , provided with the plate T' , having apertures T^2 , substantially as set forth.

13. In an electric signaling apparatus, the combination, with a series of concentric wires, of metal blocks connected with one or more 10 of the wires, a sliding spindle or post at the center of the circles described by the wires, a rotative contact-closing arm mounted to turn on said spindle and running on said metal blocks, a sleeve on the sliding spindle 15 or post, contact-pieces resting against the sleeve and connected electrically with resist-

ance-coils, a contact-piece at the side of the sleeve, which contact-piece is connected electrically with the rotative arm on the spindle, and of a check mechanism which checks the 20 upward movement of the sliding spindle at different elevations of said spindle, according to the different positions of the contact-closing arm on the spindle, substantially as shown and described. 25

In testimony that I claim the foregoing as my invention I have signed my name in presence of two subscribing witnesses.

GÜSTAV WILHELM MAXIMILIAN CONZ.
